(57) **CLAIM**

The ornamental design for the fluid dispensing nozzle, as shown and described.

DESCRIPTION

FIG. 1 is a perspective view of the fluid dispensing nozzle and is rotationally symmetric with the other sides;

FIG. 2 is a front elevation view thereof;

FIG. 3 is a rear elevation view thereof;

FIG. 4 is a side elevation view thereof; and,

FIG. 5 is a side elevation view thereof rotated 30° about the longitudinal axis relative to the view of FIG. 4.
